US00D620983S

(12) **United States Design Patent**
Hill et al.

(10) **Patent No.:** **US D620,983 S**
(45) **Date of Patent:** **** Aug. 3, 2010**

(54) **DISPLAY SIGN**

(75) Inventors: **G. Roland Hill**, Stockport (GB); **Samuel George Hill**, London (GB)

(73) Assignee: **Contra Vision Ltd.**, Cheshire (GB)

(**) Term: **14 Years**

(21) Appl. No.: **29/344,621**

(22) Filed: **Oct. 1, 2009**

(51) **LOC (9) Cl.** **20-03**

(52) **U.S. Cl.** **D20/10; D20/43**

(58) **Field of Classification Search** **D20/10, D20/19, 29, 39-43, 99; 40/124.01-124.04, 40/124.06, 124.07, 124.16-124.19, 124.191, 40/299.01, 310, 360, 538, 540-542, 584, 40/603, 606.12, 611.1, 626, 639, 642.02, 40/650, 700, 738; D6/300, 310, 314; D10/104, D10/109; D7/691; 229/107, 117.01; 248/441.1; 283/56, 71, 81; 362/220, 812**
